UNITED STATES PATENT OFFICE.

WILLIAM J. PALM, OF MINNEAPOLIS, MINNESOTA.

WASTE-PAPER PRESS.

1,242,232.

Specification of Letters Patent.

Patented Oct. 9, 1917.

Application filed June 16, 1916. Serial No. 103,914.

To all whom it may concern:

Be it known that I, WILLIAM J. PALM, a citizen of the United States, residing at Minneapolis, in the county of Hennepin and State of Minnesota, have invented certain new and useful Improvements in Waste-Paper Presses; and I do hereby declare the following to be a full, clear, and exact description of the invention, such as will enable others skilled in the art to which it appertains to make and use the same.

My invention has for its object to provide an extremely simple and highly efficient press especially adapted for use in pressing and baling waste paper, but adapted, nevertheless, for several analogous uses. As is well known, waste paper has considerable commercial value, and it has become the practice in buildings, institutes, and even in private homes, to save and sell accumulated waste paper. When placed in sacks, it is bulky. For this purpose, large and expandible presses have usually been employed.

My invention provides an inexpensive press, which, while it may be made in any desirable size, is, nevertheless, especially adapted to be made in comparatively small sizes, such as will be found convenient for daily use in public buildings, school houses, stores, flats, apartment houses, and the like, and even in private dwellings.

In the accompanying drawings which illustrate the invention, like characters indicate like parts throughout the several views.

Referring to the drawings:

Fig. 1 is a side elevation of the press, some parts being broken away and some parts being sectioned;

Fig. 2 is an end elevation of the press; and,

Fig. 3 is a vertical section taken on the line $z^3 z^3$ of Fig. 1.

The press comprises a strong, rectangular box 1, preferably made of wood and provided with a displaceable side 2. The displaceable side 2, as shown, is connected to the bottom of the box by hinges 3 and is adapted to be rigidly locked to the box in a closed position by suitable lock devices shown as in the form of hooks 4 pivoted to the ends of the box and engageable with eyes or lugs 5 on the end edges of the said displaceable side. The said displaceable side 2 is also preferably provided at its ends with laterally projecting brackets or metal

straps 6 that overlap the ends of the box to prevent spreading thereof.

Working loosely within the box, and removable therefrom, is a presser plate or follower 7 also preferably constructed of wood and shown made up of longitudinal boards and cross cleats. For holding the presser plate 7 in different positions, and against the force of the compressed waste paper y , said presser plate is provided with oppositely projecting pairs of hinged lock dogs or pawls 8 that are engageable with suitable bearing surfaces on the sides of the box. The said dogs 8 may be, and preferably are, ordinary metal hinges, each having one wing rigidly attached to an end cleat of the presser plate and having the pivoted wings free for engagement with serrated or ratchet-like metal bars or cleats 9 rigidly secured, two to the fixed side, and the other two to the displaceable side of the box. These serrated bars 9 positively prevent back-slipping of the presser plate and always hold the said presser plate down as far as it is pressed until the pivoted wing dogs are retracted or moved out of engagement with the ratchet bars 9. The waste papers must, of course, be placed in the box while the presser plate 7 is removed therefrom. The presser plate then being placed on top of the waste paper, a person may step thereon, and with his weight, compress the paper at the bottom of the box, or if desired, a lever may be employed for this purpose. At any rate, when the lock bars 8 are turned outward, and the presser plate is forced downward, the said pawls will follow up their engagement with the strips 9 and will hold the presser plate in the lowermost position in which it may be forced, so that the waste paper may be held under compression until it has set or lost most of its tendency to expand. In fact, waste paper once properly compressed, will expand but very little. When it is desired to remove the presser plate, the hinged wings of the dogs 8 must be turned backward.

For binding the compressed bales of paper, wire will usually be employed. These binding wires y^1 will be placed within the box before the waste paper is introduced, and one end of each thereof may be attached to a projection which has a screw eye 10 applied to the upper edge of the fixed side of the box, the other ends of the binding wires are brought outward through vertical

slots 11 provided in one of the sides of the box, and preferably formed in the displaceable side 2. The manner of binding of these wires may be varied, but it would usually 5 be accomplished as follows:

Before the last pressure is applied to the paper in the box, the presser plate 7 will be removed and those ends of the binding wires which have previously been attached 10 to the studs or screw eyes 10 will be loosened therefrom, turned over the top of the paper and brought outward through the respective slots 11. Then the presser plate will be again inserted in the box, and the pressure 15 again applied on the paper bale, and while the bale is thus compressed, the projecting ends of the binding wires may be twisted together through the slots 11. This being done, the presser plate should be removed 20 and the displaceable side 2 opened up, thereby permitting the compressed and bound bale of waste paper to be removed from the box.

What I claim is:

25 1. A press of the kind described, comprising a box and a presser plate working therein, said box having a displaceable side normally locked thereto but capable of being moved laterally to facilitate the removal 30 of the bale, the said presser plate having a dog engageable with said displaceable side to hold said presser plate in different adjustments in said box, lateral movement of said displaceable side serving to disengage 35 the same from the dog of said presser plate.

Copies of this patent may be obtained for five cents each, by addressing the "Commissioner of Patents, Washington, D. C."

2. A press of the kind described, comprising a box and a presser plate working therein, said box having a fixed side and an opposing laterally displaceable side normally locked thereto but capable of lateral 40 movement to facilitate removal of the bale, the said fixed and displaceable sides of said box having opposing serrated bars on their inner surfaces, and said presser plate having lock dogs engageable with the said serrated bars to hold said presser plate in different 45 adjustments, lateral movement of said displaceable side serving to disconnect the same from the coöperating dog of said presser plate.

50 3. A press of the kind described, comprising a rectangular box having fixed ends, one fixed side and one laterally displaceable side, means for locking said displaceable side to said box and for releasing the same, serrated bars arranged in pairs and secured to the inner surfaces of the fixed and displaceable sides of said box near the ends thereof, and a presser plate working in said box and provided with dogs that engage the said serrated bars, lateral movement of said displaceable side serving to disconnect said dogs from said serrated bars.

55 In testimony whereof I affix my signature in presence of two witnesses.

WILLIAM J. PALM.
